CLAIM

The ornamental design for a frame for personal mobility vehicles as shown and described.

DESCRIPTION

The patent or application file contains at least one drawing executed in color. Copies of this patent or patent application publication with color drawing(s) will be provided by the Office upon request and payment of the necessary fee.

1. Frame for personal mobility vehicles
2. Frame for personal mobility vehicles

1.1 : Front

1.2 : Back

1.3 : Right

1.4 : Left

1.5 : Top

1.6 : Bottom

1.7 : Perspective

1.8 : Reference perspective of the frame in three-wheel vehicle

1.9 : Reference perspective of the frame in four-wheel vehicle

2.1 : Front

2.2 : Back

2.3 : Right

2.4 : Left

2.5 : Top

2.6 : Bottom

2.7 : Perspective

2.8 : Reference perspective of the frame in three-wheel vehicle

(Continued)

2.9 : Reference perspective of the frame in four-wheel vehicle

Blue-colored parts in reproductions **1.1** through **2.9** are not part of the claimed designs; the shading in reproductions **1.1** through **2.9** represents three-dimensional shapes of the surfaces; the shading does not illustrate surface ornamentation or decoration; no protection is claimed for the color of the designs; the frame for personal mobility vehicles is a part for personal mobility vehicles having a seat on which one person sits to ride the personal mobility vehicles as shown in reproductions **1.8**, **1.9**, **2.8**, and **2.9**; the reference reproductions **1.8**, **1.9**, **2.8**, and **2.9** do not form part of the claimed designs.
